BILLFOLD

Prince A. Gardner, Jr., St. Louis, Mo.

Application August 12, 1932, Serial No. 628,481

1 Claim. (Cl. 150—38)

This invention relates to billfolds of the type having means for closing the open sides of the pockets and for holding the billfolds closed or folded. The invention comprises a billfold, or 5 pocket case adapted for many uses, including an outer wall of an elongated pocket having two end portions united by a hinge portion of appropriate length and of less vertical width than the end portions and having its upper edge terminating 10 below the upper edges of the end portions to provide a space between the upper edges of the end portions of said outer wall; flexible wall elements forming inwardly open longitudinally spaced pockets in connection with the inner sides 15 of the respective end portions of said outer wall, the inner ends of said flexible wall elements being spaced apart a distance at least equal to and preferably greater than the longitudinal length of said hinge portion of said outer wall in order 20 not to interfere with the functioning of said hinge portion irrespective of the amount of the contents of any of the pockets of the billfold; and a panel bridging the space between the inner ends 25 of said inwardly open pockets and cooperating with the walls thereof and with said outer wall to form an elongated pocket, said panel having sliding arrangement in one of said inwardly open pockets so that buckling or rolling of the panel 30 is prevented irrespective of the amount of contents of the billfold.

An object of the invention is to provide a billfold embodying these features and others hereinafter mentioned or otherwise made apparent.

Other objects of the invention are to provide a billfold embodying the foregoing and other advantageous features of arrangement and construction herein disclosed, reference being made to the annexed drawing, in which—

Fig. 1 is a view showing the outside of the billfold in its open or extended position, parts of the end portions of the outer wall being broken away to disclose other essential features.

Fig. 2 is a view showing the inside of the billfold open or extended, parts of the inner pocket forming walls being broken away to disclose essential features of the invention.

Fig. 3 is a perspective view of the billfold closed.

Fig. 4 is a longitudinal sectional view of a portion of the billfold in its open or extended position and taken approximately on the line 4—4 of Fig. 2.

Fig. 5 is a vertical cross sectional view of one end portion of the billfold approximately on the line 5—5 of Fig. 2.

55 The outer wall of the billfold is composed of

leather, or other appropriate flexible material, and is preferably made of a single piece of said material shaped and formed to provide end portions 1 and 2 connected by a hinge portion 3 of appropriate length to connect the end portions 1 5 and 2 when they are folded in spaced relationship, as when the billfold is wholly or partly filled and the wall portions thereof are spaced apart when the billfold is closed. The hinge portion 3 is of less vertical width than the vertical width 10 of the end portions 1 and 2 of the outer wall, the lower edge of the hinge portion 3 being in alignment with the lower edges of the portions 1 and 2 and the upper edge of the hinge portion 3 being spaced below the upper edges of said portions 1 and 2, thereby providing a space 4 between 15 the adjacent ends of the end portions 1 and 2 at the upper side of the billfold. This space 4 defines the width of the hinge portion 3.

A flexible and pliable lining 5 of the same shape 20 and approximately the same length and width as the outer wall above described is mounted against the inner side of said outer wall.

An inwardly open pocket having its walls of less length than the length of the wall 1 and composed of flexible and pliable material is provided in connection with the inner side of the end portion 1 of the outer wall. This inwardly open pocket includes an inner wall forming portion 6, an outer wall forming portion 7, both of less 25 vertical width than the vertical width of the wall portion 1 and of greater vertical width than the vertical width of the hinge portion 3. The lower and outer end edges of said wall forming portions 6 and 7 are connected to the lower and outer end 30 edges of the portion 1 of the outer wall and have their upper edges connected with each other and unattached to the outer wall.

An inwardly open pocket is provided in connection with the inner side of the wall portion 2, 40 the same comprising a wall portion 8 and a frame or wall portion 9, both of less width than the portion 2 and of greater vertical width than the vertical width of the hinge portion 3 and having their lower and outer edges connected with the 45 lower and outer edges of the portion 2 of the outer wall and their upper edges connected with each other and otherwise unattached to any other portion of the billfold.

The inner ends of the walls 6, 7, 8 and 9 do not 50 extend to the hinge portion 3 of the outer wall, so that said hinge portion 3 is free to function without interference or obstruction by these inner pocket forming walls.

A panel 10 in connection with the inner end 55

of one of the inner pocket forming walls and having its upper edge below the upper edges of the walls 6, 7, 8 and 9 extends across the space between said inner pocket forming walls and into 5 the opposite inwardly open pocket terminating short of the outer or bottom end of said opposite inwardly open pocket to provide a free sliding action therein when the billfold is opened and closed irrespective of the amount of contents of 10 the billfold. If the panel 10 is composed of a separate piece of material, it must be characterized by sufficient flexibility and pliability to fold freely with the hinge 3 and has one end attached to the inner end of one of the inner pocket forming walls by stitches 11 or other appropriate fastening means. As shown, the stitches 11 attach one end of the panel 10 to the inner end of the wall 8, although the panel 10 may be attached elsewhere, if desired. The opposite end of the 15 panel 10 is attached to a section 12 of flexible and pliable and freely foldable material, such as a textile fabric, by stitches 13, or other appropriate fastening means. The outer end of the section 12 is attached to the outer end of the wall 6. 20 Sections 14 and 15 of flexible and pliable material are attached to the upper and outer end edges of the wall portions 1 and 2, respectively. These sections 14 and 15 are in the form of elongated tapes and have their inner ends extending 25 into the space 4 and their outer ends extending downwardly along the outer ends of the portions 1 and 2 of the outer wall. These sections 14 and 15 constitute inwardly extended wall elements which extend toward each other beyond the adjacent surfaces of the pocket walls when the billfold is folded or closed and their adjacent edges are provided with interlocking fingers 16 and 17, respectively, which interlock upon a well known principle and mode of operation. A slide 18 is 30 mounted in connection with the two series of fingers 16 and 17 and is movable along said fingers when the billfold is closed or folded in order to interlock the fingers 16 and 17 and to release said fingers. The arrangement is such that when the 35 slide 18 is moved to its position in the space 4, the fingers 16 and 17 are disengaged from each other and the billfold may freely open; and when the slide 18 is moved outwardly along the series of fingers to the position shown in Fig. 3, the fingers 16 and 17 are interlocked by such outward movement and remain interlocked until the slide is moved in the opposite direction. The slide is 40 equipped with a pivoted handle member 19 which affords convenient means for operating the slide. 45 The inner edges of the wall members 14 and 15 extend between the lining 5 and the wall portions 1 and 2. A row of stitches 20 passes through the lower and outer end edges of the outer wall, the lining 5, the wall members 6 and 7 and the wall members 8 and 9 and thereby attach the inner pocket forming walls in proper relationship to each other and to the outer wall. The stitches 20 also pass through the outer end of the section 12, thereby securing the outer end of said section 12 to the outer end of the billfold without interfering with the free sliding action of the panel 10 but preventing said panel 10 from being withdrawn from the pocket in which it extends for 55 sliding movements.

70 A row of stitches 21 in continuation of the row of stitches 20 extends along the upper edge of the outer wall, passing through the end wall portions 1 and 2, the tapes 14 and 15 and the lining

5, thereby fastening these parts securely together. The stitches 21 also extend across the upper marginal portion of the hinge 3.

The wall portion 9 may be in the form of an open frame, as shown, and the opening in said frame may be closed by a transparent panel 22, so that the contents of the pocket formed by the panel 22 and the wall 8 are partly visible. The non-transparent inner end 23 of the frame 9 covers and conceals the end of the panel 10 and also covers and conceals the stitches 11.

When the billfold is closed, the flexible and pliable wall forming members 14 and 15 extend a substantial distance toward each other and cover and conceal and close the opening to the elongated pocket between the outer wall and its co-operating pocket forming walls. This elongated pocket is designed and adapted to receive and contain articles having a vertical width such that they will not interfere with the operation of the latching and unlatching slide 18.

An additional pocket may be provided in this billfold, if desired. As shown, a wall 24 has its lower and outer end edges engaged by the stitches 20 and its upper marginal portion 25 extended over the connection uniting the wall portions 6 and 7 and downwardly into the pocket or space between the lining 5 and the wall forming portion 6. This upper marginal portion may be attached to the wall forming portion 6 by stitches 26, or other appropriate fastening means, substantially below the upper portion of the pocket and concealed within the pocket or space between the lining 5 and the wall forming portion 6.

It is clearly apparent that this billfold is well 35 designed and adapted for application to many uses and to contain many articles of different types. The fastening devices in cooperation with the walls 14 and 15 with which they are united provide an effective closure for the billfold, so 40 that it is impossible for the contents of the billfold to work out or for other articles of materials to work into the billfold.

The construction and arrangement of the parts may be varied within the scope of equivalent limits without departure from the nature and principle of the invention. I do not restrict myself in any unessential respects, but what I claim and desire to secure by Letters Patent is:

A device of the character described comprising 50 an outer wall having a transverse foldable portion intermediate of its ends, pocket walls having their lower and outer edges attached to the lower and outer edges of said outer wall respectively and having their inner ends above said lower edges 55 unattached to said outer wall and spaced apart an appreciable distance and forming spaced inwardly open pockets, a panel connected with one of said pocket walls and bridging the space between said respective pocket walls and extending into the opposite pocket and cooperating with said pocket walls and with said outer walls to form an elongated pocket, wall elements attached to the upper and outer edges of said outer wall and extending toward each other beyond the adjacent surfaces of said pocket walls when said outer wall is folded, and fastening means in connection with the edges of said wall elements for holding said wall elements together when said outer wall is folded.

PRINCE A. GARDNER, JR.
